OTTO LE GRAND DILWORTH, OF HARTFORD, CONNECTICUT.

ARTIFICIAL LIMB.

1,385,669.

Specification of Letters Patent.

Patented July 26, 1921.

Application filed July 22, 1919. Serial No. 312,571.

To all whom it may concern:

Be it known that I, OTTO LE GRAND DILWORTH, a citizen of the United States, and a resident of Hartford, in the county of Hartford and State of Connecticut, have invented 5 a new and Improved Artificial Limb, of which the following is a specification.

An object of the invention, among others, is to provide an artificial hand that may be 10 readily operated and the movements of which shall closely imitate those of natural members.

One form of device embodying my invention and in the construction and use of which 15 the objects herein set out, as well as others, may be attained, is illustrated in the accompanying drawings, in which—

Figure 1 is a view of my improved hand and arm with parts broken away to show 20 construction, the forearm being bent upwardly.

Fig. 2 is a similar view but looking toward the back of the hand.

Fig. 3 is a detail view illustrating mechanism for moving the thumb.

Fig. 4 is a view of a fragment of the thumb illustrating the construction thereof.

Fig. 5 is a detail view, scale enlarged, of 30 the finger operating mechanism with parts broken away to show construction.

Fig. 6 is a detail view on plane denoted by dotted line 6—6 of Fig. 5.

Fig. 7 is a detail plan view of the supporting bar for the finger actuating mechanism.

Fig. 8 is a detail view illustrating a portion of the finger operating mechanism and the means for retaining the parts in unlocked condition.

Fig. 9 is a detail view in section through the cover of the hand and illustrating the mechanism for retaining the parts in unlocked condition.

In the accompanying drawings the number 45 10 indicates the upper arm and 11 the forearm of my improved device, the former being hollow, thus providing a recess to receive the stump of the natural arm. The fore and upper arms may be constructed of 50 any suitable, light material, common to structures of this class and the forearm is preferably hollow from end to end, and it is cut away on one side as at 12. The lower end of the upper arm 10 projects into the 55 end of the forearm and these two members are pivotally united as by a pivot 13 secured

in the member 10 with its ends projecting beyond the sides of said member and entering supporting straps 14—15 secured to opposite sides of the forearm and projecting 60 beyond its upper end, said straps having a swinging movement on said pivot.

The hand may be attached to the arm as by means of a wrist piece 16 pivotally secured to the arm in any desired manner, the 65 hand being pivotally secured to the wrist piece as may be desired. A thumb is movably attached to the hand in the usual position, the structure herein shown comprising a base 17 having a shank 18, said base fitting 70 within a socket 19 at one edge of the hand, and as shown in Fig. 3 of the drawings. The base member is rotatably held in place as by means of a hollow nut 20 fitting the screw threaded end of the shank 18. An ear 22 75 extends from the center of the base, the outer end of this ear being formed on the arc of a circle. An inner thumb member 23, substantially round in cross section, has its inner end oppositely formed to correspond 80 to the base above described, that is, said thumb member has a groove formed by ears 24 to receive the ear 22. The outer end of the inner thumb member is formed to substantially the shape of the inner end thereof, 85 and a tip member 25 of the thumb has its inner end oppositely formed to the thumb member 23, that is, with a cavity, the bottom of which is formed on the arc of a circle to receive the ears at the outer end of the inner 90 thumb member, an ear 26 from the tip member fitting the groove in the outer end of the member 23. A spring 27, located in a recess between the inner and tip thumb members, forces the latter back to its open 95 position. The thumb may be turned on the axis of the base as by means of the other hand, and it has a lug 28 projecting from an overhanging part 29 on the lower edge of the thumb member 23 that overlies the 100 edge of the socket 19, said lug being adapted, when the thumb is in one rotatable position, to enter a notch 30 in the edge of said socket and permit the member 23 to bend toward the hand. A thumb actuating cord 80 is 105 secured to the front side of the tip 25, said cord extending through a hole in the thumb member and base and through a passage 81 into a chamber 82 within the hand. Said cord will yield sufficiently to permit the lug 110 28 to be removed from the notch 30. This chamber preferably opens from the back

of the hand and is closed by a cover 34 that may be secured in place in any desired manner.

Finger and thumb actuating mechanism 5 is inclosed within the chamber 82, such mechanism, in the structure herein shown, comprising side plates 84 secured to the side walls of the chamber 82 opposite one another, each of these plates being thickened 10 between its ends and having a guide groove 85. Cover rests 86 project from one edge of each plate and notches 87—88 are formed in the opposite edges of said plate, that is, in that edge of said plate toward the front 15 of the hand. The plates are secured in place in any desired manner, as by screws projecting through the outer edges of the hand. A supporting bar 89 extends across the chamber, one end of the bar projecting into 20 the notch 88 and the opposite end into the notch 87, the bar at this end being of a width narrower than that of the notch so that the bar may have a slight lateral movement within said notch. A spring 132 having 25 one end secured to a side plate and its other end engaged with the supporting bar holds it at one limit of its play as shown in Fig. 5 of the drawings.

A carrier plate 91 is pivotally supported 30 at one end on the bar 89, preferably on a boss 92 thereon. This carrier plate has a groove extending lengthwise thereof to receive a retaining slide 93 that is movable in a direction lengthwise of the carrier plate. 35 A hollow stud 94 is secured to the carrier plate 91 and projects through a slot in the retaining slide. A ratchet wheel is rotatably mounted on the stud 94, this ratchet having the usual peripheral teeth 95 and a set of holding teeth 96. The holding teeth 40 are engaged by a carrier plate holding dog 97 pivotally mounted on the carrier plate and with its free end adapted to engage notches in the ends of the holding teeth, or 45 in the spaces between the holding teeth. A retaining slide actuating spring 98 has one end in engagement with a screw stud 99 secured to the supporting bar, in the structure shown herein this stud passing through a 50 filling plate 100 tightly secured within the groove in the carrier plate and through said plate. The other and active end of said spring thrusts against a carrier plate actuating stud 101 that is screw threaded into 55 the dog 97 and projects on the opposite side thereof and loosely into an opening in the retaining slide 93, the slide and dog being thus connected and the spring engaging the dog with the holding teeth of the ratchet and 60 also moving the retaining slide in its groove in the carrier plate.

A carrier plate and pawl actuating lever 102 is pivotally mounted on the stud 99 and has a slot through which a screw pin 103, 65 secured to the carrier plate, extends. A fin-

ger actuating cord 90 has one end secured to said actuating lever, the opposite end being disposed of in a manner to be hereinafter set out. An actuating pawl 105 is pivotally mounted on the lever 102 with its teeth normally held in engagement with the ratchet teeth 95 as by means of a spring, one end of which is secured to the pawl and the other end of which is secured to the stud 94.

A retaining pawl 106 is pivotally secured 75 to the carrier plate 91 on the opposite side thereof from the mechanism just hereinabove described, the end of said pawl being adapted to engage the teeth of a retaining rack 133 secured to the supporting bar 89. 80 A retaining pawl actuating pin 134 projects from the pawl through a slot 109 in the carrier plate 91 and into a notch in the edge of the retaining slide 93, as shown in Fig. 5 of the drawings. The thumb actuating 85 cord 80 is secured to the carrier plate, that, in its swinging movement, pulls upon or releases said cord and thus actuates the thumb member or permits it to be actuated.

A finger actuating rod 135 has its ends 90 sliding in the guide grooves 85 in the side plates 84, this rod passing through knuckles 111 formed on a tie plate 112. This plate is secured to the stud 94 as by means of a headed screw 113. A screw 114 projects 95 through the tie plate and serves as a fastening for one end of a link 115, the other end of said link being secured to the end of the hollow stud 94, as shown in Fig. 6 of the drawings. The link 115 has a sliding movement in a groove in a rocker 116 pivotally secured to a lateral projection from the supporting bar 89 and as by means of a pivot secured to said bar and extending into a hole 117 in the rocker (see dotted lines in Fig. 7 100 of the drawings). This connection between the carrier plate and the finger actuating mechanism and comprising the tie plate and the link prevents undue lateral play of the rod 135, and the location of one end of the 105 supporting bar 89 in the notch 87 permits a slight movement of said bar sufficient to relieve rigidity in the finger action and permit a certain elasticity thereof. This is an important feature of my invention, as the 110 link 115 being guided in its movements by the groove in the rocker, undue lateral play 115 is prevented and extreme steadiness of finger action is obtained.

The fingers each comprises a base section 118 and a tip section 119, the fingers being pivotally attached to the hand as by means of a finger pivot 120 extending laterally across the hand and through its side parts. A finger actuating lever 124 is pivotally attached at one end to each of the tip sections 119 of the fingers, the opposite end of each of said levers being attached to the finger actuating rod 135. Backward movement of the levers 124 from their positions beyond 125

a point to place the fingers in their open positions, is prevented by a finger pivot 125 in each finger joining the tip and base sections thereof, the levers being located in 5 deep slots cut into the fingers from their front sides and each lever having a notch to receive said pivot. Each of said levers also has a cam slot 126 formed by a cam prong 127 extending from the back thereof. The 10 back edge of each lever engages the pivots 120 and 125 and the back edge of each prong engages a base section operating pin 128 extending across the slots in the fingers at the inner end of each base section thereof or 15 the back edges of the levers may directly engage the bottoms of the slots in the base sections. The grooves 85 that receive the ends of the actuating rods 135 are inclined with respect to a plane passing centrally through 20 the hand more or less parallel with the back and front thereof, and as shown in Fig. 1 of the drawings.

This construction provides for a peculiar movement of the fingers and one that is 25 found especially desirable in enabling the hand to be used for different purposes for which it is required. The finger actuating rod 135 being moved by its actuating mechanism, each of the levers 124 is pulled to 30 ward the rear of the chamber 82. The rod 135 traveling along the inclined slots causes the levers 124 to rock on the finger pivot 120 as a fulcrum carrying the outer ends of the levers forward and moving the finger 35 tips in this direction. This rocking movement of the levers also acts against the several pins 128 thus moving the outer ends of the base sections of the fingers forward, carrying with them the tip sections, so that 40 the tip sections have an accelerated movement caused by simultaneous pivotal movement of the base and tip sections.

The finger actuating cord 90 passes over and under sheaves 130-131 and through an 45 opening in the wrist to the outside thereof, as shown in Figs. 2 and 5 of the drawings, and along the forearm through proper guides to a point of attachment to a vest (not shown) on the body of the wearer.

50 It will be noted from the above description that a pull upon the cord 90 will move the lever 102, causing the pawl 105 thereon to move the ratchet one step, which, with the parts in the position shown in Fig. 5 of the 55 drawings, would move the holding teeth 96 from engagement with the holding dog 97. This action will permit the retaining slide 93 to move under the force of the spring 98 into position with the pawl 106 engaging the 60 teeth of the rack 133. The lever 102 having been moved to engage the opposite end of its slot with the pin 103 a continued pull upon the cord 90 will cause the carrier plate 91 to be swung on its pivot and it will be 65 retained by the pawl 106 in any position to

which it will be moved. This movement of said plate exerts a pull upon the finger actuating levers 124, imparting to them a closing movement as hereinbefore described, and in which position they will be held. This 70 pull upon the cord 90 may be obtained by lowering the shoulder of the stump, to which the arm is attached, the latter being thus extended away from the anchoring strap (not shown) to which it is secured. 75

It will be noted that the thumb actuating cord 80 is attached to the carrier plate on the opposite side of the pivot 99 from that at which the cord 90 is connected and nearer to said pivot so that the amount of thumb 80 movement is less than that of the fingers.

The next succeeding pull upon the cord 90 will repeat the operation of the lever 102 and the pawl, but the dog 97 will be engaged with one of the holding teeth and the pawl 85 106 will be disengaged from its retaining rack. Upon force being now released from the cord 90 the main spring 136 will move the parts to their former position as shown in Fig. 2 of the drawings, the fingers being 90 thus opened and the lever 102 being returned to its former position under the action of the spring that operates upon the pawl 105.

It will be understood that much of the hand will have a soft covering, as a form of 95 glove, that may be of any desired color.

The forearm may be locked in different positions by means of a locking bar 35 pivotally attached to the upper arm and extending into the lower arm, said locking bar having 100 a longitudinal slot 36 with locking notches 37 at intervals along the edge of the slot to receive a locking pin 38 upon which a locking lever 39 is pivotally mounted, said pin being secured in a bridge 40 extending 105 across the opening in the forearm and secured to the walls thereof. The end of the lever 39 projects through the forearm to the outer surface thereof where it may be manually operated. The lever 39 is in the form 110 of a bell-crank lever one arm having lips 41 projecting from the lever and lying upon opposite sides of the bar 35. From this description it will be seen that the lever 39 being swung on its pivot the bar 35 will be 115 moved in one direction to disengage the pin 38 from one of the notches and the forearm being then bent to another position the pin will be engaged with another notch and the forearm may thus be locked in its new position. 120

In order that the fingers may be freely closed and opened without being locked in either position, I provide a lock release, in the mechanism herein shown this release 125 comprising a lock releasing cam 42 secured to the inner end of a lock releasing shaft 43 mounted in the cover 34 and operating against the stud 101 to force the dog 97 from engagement with the holding teeth 96, 130

4
this cam being of such shape that it will retain the dog in this disengaged position. Said shaft extends through the cover to the back of the hand and is provided with a releasing arm 44 having a knob 45 by means of which the lock may be manually operated. Said knob will project only a slight distance from the arm 44, just enough to allow said arm to be operated. Any means may be employed for holding the arm 44 in different positions, but it will be found that the curve of the cam will be slight enough to obtain this result and thereby answer all purposes.

15 The bar 35 may be retained in position with the pin 38 engaged with or disengaged from the notches as by means of a spring 74 located on the pivot of the lever 39 and pressing with one end against the inside of the 20 forearm and with its opposite end against said bar, as illustrated in Fig. 2 of the drawings.

In a prior application filed by me March 23rd, 1917, of Serial Number 157,032, an 25 arm and hand mechanism is illustrated and described embodying the following as a portion of its features:

A socket piece 46 secured in any desired manner in the opening in the lower end of 30 the forearm and having a recess opening into said arm, a hollow shaft 47 rotatably mounted in said socket piece and secured to the wrist piece 16, a coupling collar 48 slidably mounted on the hollow shaft and operated by a lever 49, said collar receiving a 35 wrist turning cord 56, the operation of which to turn the wrist is described in my aforesaid application. A more complete description of these parts is omitted herein as not necessary to the improvement as embodied 40 in the present case and reference is hereby made to said copending application for such further information as may be desired with respect to said construction.

45 The present improvement embodies means for holding the hand in different positions with respect to the wrist piece 16, said hand 67 being mounted on a pivot 66 and having notches 68. The pivot 66 is mounted in 50 projecting bearings 65 extending from the wrist piece, the latter having a circular shaped recess to receive the end of the hand, the latter being preferably formed on the arc of a circle.

55 A locking bolt 69 is located in the hollow shaft 47, said bolt being hollow and having a spring 70 located in the recess therein and thrusting against a pin 71 projecting through said hollow sleeve. The end of the 60 bolt has a lug 72 that is forced by said spring into the notches 68, a hand locking lever 73 being engaged with the locking bolt as a means for operating it. This lever is pivotally mounted in the wrist piece 16 and projects out at the front thereof a short dis-

tance and by its use the hand may be locked in one of several positions into which it may have been placed.

In accordance with the provisions of the patent statutes, I have described the principles of operation of my invention, together with the device which I now consider to represent the best embodiment thereof; but I desire to have it understood that the device shown is only illustrative, and that the invention may be carried out by other means.

I claim—

1. An artificial limb including a hand, fingers attached to the hand for bending movement, means for effecting bending movement of the fingers, mechanism movable independently of the bending means for locking the fingers in a bent position, and means operated always in one direction for effecting locking and unlocking movement, of said locking mechanism.

2. An artificial limb including a hand, fingers attached to the hand for bending movement, means for effecting said bending movement, mechanism movable independently of the bending means for locking said means with the fingers in bent position and including a member movable in one direction to effect locking and unlocking movement thereof, and a cord attached to said member to operate it.

3. An artificial limb including a hand, fingers attached to said hand for bending movement, means for bending the fingers, mechanism movable independently of the bending means for locking said fingers in bent position, and an actuator connected with the bending means and with the locking mechanism for operating both.

4. An artificial limb including a hand, fingers attached to the hand for bending movement, means for bending the fingers, locking mechanism movable independently of the bending means for retaining the fingers in bent position, said mechanism including a toothed member to receive and hold said locking member, and means for operating said locking member.

5. An artificial limb including a hand, fingers attached to said hand for bending movement, a rocking member connected with said fingers to bend them, a lock movably mounted on said rocking member, mechanism for operating said lock and movable independently of the rocking member, and means for operating said lock actuating member.

6. An artificial limb including a hand, fingers attached to said hand for bending movement, a locking member to lock the fingers in bent position, a lock operating member having teeth to retain the locking member in unlocked position, and an actuating member operatively connected to move the fingers, to operate the lock actuating member.

- member and to move the latter step-by-step always in one direction.
7. An artificial limb including a hand, fingers attached to the hand for bending movement, a rocking member connected with said fingers to bend them, a locking member mounted on the rocking member, a toothed wheel rotatably mounted on the rocking member and having means to retain the locking member in one position, and an actuating member operatively connected with said toothed wheel and having movement independently of said rocking member.
8. A hand having fingers attached thereto for bending movement, a carrier plate operatively connected with the fingers, a retaining slide movably mounted on the plate, an actuating lever pivotally mounted, connections between said lever and retaining slide to operate the latter and including means for holding the slide in one position, and means for connecting the actuating lever with the carrier plate after the lever has effected part of its movement.
9. A hand having fingers attached thereto for bending movement, a pivotally mounted carrier plate, a retaining slide movably mounted on the plate, a locking dog to retain the slide in one position, a toothed wheel pivotally mounted on the plate and connected with said retaining slide to retain it in one position, and a ratchet and pawl connection between said lever and said toothed wheel.
10. A hand having fingers attached thereto for bending movement, a carrier plate connected to bend said fingers, a retaining slide, an actuating lever operatively connected with said slide and movable independently of said carrier plate, and means for connecting the lever with the carrier plate after the lever has effected part of its movement.
11. A hand having a finger attached thereto for bending movement, a movably mounted carrier plate operatively connected to bend said finger, a retaining slide movably mounted on said plate, a holding dog pivotally mounted on said plate and operatively connected with the slide to operate it, and means for operating said dog.
12. A hand having a finger attached thereto for bending movement, a movably mounted carrier plate operatively connected to bend said finger, a retaining slide movably mounted on said plate, a dog pivotally supported on said plate, and slide operating mechanism including a toothed member arranged to engage said dog to operate it.
13. A hand having fingers attached thereto for bending movement, a movably mounted supporting bar, a carrier plate movably mounted on said bar and operatively connected to bend said fingers, a retaining slide movably mounted on said plate, and means for operating said plate.
14. A hand having fingers attached thereto for bending movement, a supporting bar having a limited yielding movement, a carrier plate movably mounted on said bar and operatively connected to bend said fingers, and means for operating said plate.
15. A hand having a finger attached thereto for bending movement, a longitudinally movable finger actuating lever having a cam actuating surface, means for moving said lever, and means on said finger adapted to contact with said cam to effect bending movement of the finger by reason of movement of said lever.
16. A hand having a finger attached thereto, said finger comprising a base and a tip section, the base section being pivotally connected to the hand and the tip section being pivotally connected to the base section, an actuating lever pivotally connected with said tip section and having a cam actuating surface, means on the base section of the finger to contact with said cam to effect bending movement of said base section, and means for actuating the lever.
17. A hand having a finger attached thereto, said finger comprising a base section pivotally attached to the hand and a tip section pivotally connected to the base section, an actuating lever pivotally connected with the tip section and also operatively connected to bend the base section, and means for operating said lever to effect bending movement of the base section and simultaneous therewith and by reason thereof to affect an accelerated bending movement of the tip section.
18. A hand having a finger attached thereto, said finger comprising a base section pivotally attached to the hand and a tip section pivotally connected to the base section, an actuating lever operatively connected with the tip section, means for moving said lever endwise to effect bending movement of said tip section, and means for moving said lever laterally to effect accelerated movement of said tip section.
19. A hand having fingers attached thereto for bending movement, a pivotally mounted carrier plate, a locking bolt slidably mounted on the plate, a toothed wheel pivotally mounted on the plate to engage said locking bolt to retain it in one position, and a ratchet wheel and pawl connection between said lever and said toothed wheel.
20. A hand having a finger attached thereto, said finger comprising a base and a tip section, an actuating lever comprising a cam lever, a connection between said lever and said base section of the finger for operating the latter, a connection between said lever and said tip section for operating it, and means for operating the lever.
21. A hand having a finger attached thereto, said finger comprising a base and

a tip section, an actuating lever pivotally connected with the tip section and having a cam surface, a guide to contact with said cam surface to effect lateral movement of the lever, and means for drawing said lever along said guide.

22. A hand, a thumb comprising a base section swivelly supported in the hand to turn on the axis of said base section, and another section pivotally connected to the base section, and means for effecting bending movement of said pivoted section.

23. A hand, a thumb comprising a base section swivelly supported in the hand to turn on the axis of said base section, means for locking the base section against swiveling movement, another section pivotally connected to the base section, and means for effecting bending movement of said pivoted section.

24. A hand having fingers pivotally connected thereto, a swinging bar, a connection between said bar on one side of its pivot and said fingers to effect bending movement of the latter, and a connection between said bar on the opposite side of said pivot and the thumb to effect bending movement of the latter.

25. A hand having fingers attached thereto for bending movement, a finger actuating rod operatively connected with said fingers, a movably mounted member operatively connected with said rod to operate it, means to support said movable member and prevent tipping and consequent cramping action of said rod and means for actuating said movably mounted member.

26. A hand having fingers attached thereto for bending movement, a finger actuating rod operatively connected with said fingers, a sliding member connected with said rod to assist in its operation, and a guide for said sliding member to restrict sidewise swinging movement thereof.

45 27. A hand having fingers attached thereto for bending movement, a finger actuating rod operatively connected with said fingers, a movably mounted finger bending member pivotally connected with said rod, a link mounted on said pivot, means to connect the link with said rod, and a guide for said link to restrict undue swinging movement thereof and thereby prevent cramping action of the finger actuating rod.

55 28. A hand having fingers attached thereto for bending movement, a finger actuating rod operatively connected with said fingers, a movably mounted finger bending member pivotally connected with said rod at a plurality of points, and a link connecting said finger bending member and said rod, said link being secured at said points.

60 29. A hand having fingers attached thereto for bending movement, a finger actuating rod operatively connected with said

85 fingers, a movably mounted finger bending member pivotally connected with said rod, a rocker pivotally supported in proximity to said finger bending member and having a guideway, a link mounted to slide in said guideway, and means for pivotally connecting said link to said finger bending member and with said rod.

30. A hand having fingers attached thereto for bending movement, a finger actuating rod operatively connected with said fingers, a movably mounted finger bending member, a rocker supported in proximity to said member and having a guideway, a link located in said guideway and pivotally connected with said member and with said rod, and a projection from said rod connected with said link at one end and with the pivot securing the opposite end of said link.

85 31. A hand having fingers attached thereto for bending movement, a finger actuating rod operatively connected with said fingers, a movably mounted supporting bar, a finger bending member movably mounted on said bar and pivotally connected with said rod, a guide attached to said bar, and a member carried by said guide and connected to said finger bending member to prevent cramping movement of said rod.

95 32. A hand having fingers attached thereto for bending movement, a finger actuating rod operatively connected with said fingers, a movably mounted supporting bar, a rocker pivotally connected with said bar and having a guideway, a link mounted in said guideway, a finger bending member operatively connected with said rod, and a pivotal connection between said finger bending member and said link.

105 33. A hand having fingers attached thereto for bending movement, a finger actuating rod operatively connected with said fingers, a pivotally mounted supporting bar, a finger bending member mounted on said bar, a rocker pivotally mounted on said bar and having a guideway, a link mounted in said guideway and connected with said finger bending member in proximity to the pivot of said rocker, and a pivot connecting the opposite end of said link with said rod, the latter being connected with said member by means of the last mentioned pivot.

110 34. A hand having fingers attached thereto for bending movement, a finger actuating rod operatively connected with said fingers, a movably mounted finger bending member connected with said rod, a member for operating said finger bending member, a member for locking said finger bending member against movement, and mechanism for retaining said locking member in unlocked position to permit free opening and closing movement of the fingers.

115 35. A hand having fingers attached there-

120

125

130

- to for bending movement, a finger actuating rod operatively connected with said fingers, a movably mounted finger bending member pivotally connected with said rod, means for locking said member against movement, said means including a dog, and means for retaining said dog in position to prevent operation of the locking members and thereby permit free opening and closing movement 10 of the fingers.
36. A hand having fingers attached thereto for bending movement, a finger actuating rod operatively connected with said fingers, a movably mounted finger bending member connected with said rod, means for locking said member against movement, said locking means including a dog, a cam mounted in the hand structure and operatively connected with said dog to hold it in position 15 to prevent operation of the locking members and thereby permit free opening and closing movement of the fingers, and means for operating said dog.
37. An artificial limb including an upper arm and a forearm pivotally attached thereto, a locker bar pivotally connecting said members, said bar having a slot with locking notches, a stud to engage said notches to retain the bar in certain positions, and a lever in engagement with said bar to engage and disengage said notches with and from said stud.
38. An artificial limb including an upper arm and a forearm pivotally attached thereto, a support located in one of said arms, a locking bar pivotally attached to the other arm, said bar having a slot and locking notches in the edge thereof, a lever pivotally mounted on a stud extending from said support, and means engaging said lever with said bar to engage and disengage said notches from said stud.
39. An artificial limb including an upper arm and a forearm pivotally attached thereto, a bridge extending across one of said arms, a stud secured to said bridge, a lever pivotally mounted on said stud and having lips projecting from one arm thereof, and a locking bar pivotally attached to the other arm and having a slot with notches in the edge thereof, said bar resting between said lips.
40. An artificial limb including a forearm, a hand pivotally attached thereto on an axis extending transversely of the axis of the forearm, a locking bolt to positively retain the hand in different positions, means on the hand to receive said locking bolt, and means for operating said bolt.
41. An artificial limb including a forearm, a hand swivelly attached thereto and also pivotally connected therewith, a locking bolt located in line with the axis of said swivel to positively lock the hand against movement, and means on the hand to re-
- ceive said bolt to retain the hand in different positions.
42. An artificial limb including a forearm, a hand pivotally attached to the forearm, a hollow shaft swivelly connecting the hand with said forearm, a locking bolt mounted in said shaft, and means on the hand to receive said bolt to retain the hand in different positions.
43. An artificial limb including a forearm, a wrist piece, a hand pivotally attached to said wrist piece with its edge extending into a socket therein and having locking notches in its edge, a hollow shaft swivelly attaching the wrist piece to the forearm, a locking bolt located in said shaft, and a bolt operating lever extending through the wrist piece to the outside thereof.
44. An artificial limb comprising members movably mounted one with respect to another, a locking member for locking said members against movement, a lock actuator having a step-by-step movement to alternately place said lock actuator in locked and unlocked positions, and means for operating said lock actuator.
45. An artificial limb comprising members movably mounted one with respect to another, a locking member for locking said members against movement, a rotatably mounted lock actuator having a step-by-step movement to alternately place said lock actuator in locked and unlocked positions, and means for operating said lock actuator.
46. An artificial limb comprising members movably mounted one with respect to another, an operating member connected with one of said members and movable coextensive therewith, means for locking said operating member against movement, a lock actuator mounted for step-by-step movement to alternately place said lock actuator in locked and unlocked positions, and means for operating said lock actuator.
47. A hand having fingers attached thereto for bending movement, a carrier plate operatively connected with the fingers, a retaining slide movably mounted on the plate, an actuating lever pivotally mounted, connections between said lever and retaining slide to operate the latter and including means for holding the slide in one position, and means for operatively connecting the actuating lever with the carrier plate to operate the latter.
48. A hand having fingers attached thereto for bending movement, a finger actuating rod operatively connected with said fingers, a member movably mounted to actuate said rod, a sliding member pivotally connected with said actuating member, and means for guiding said sliding member while permitting lateral play thereof.
